Primary Examiner — Robert M Spear*Assistant Examiner* — Marissa J Cash(74) *Attorney, Agent, or Firm* — Brinks Gilson & Lione**CLAIM**

I claim the ornamental design for a reinforcement ring for beverage capsule, as shown and described.

DESCRIPTION

FIG. 1 is a top perspective view of a reinforcement ring for beverage capsule of the present invention;
FIG. 2 is a bottom plan view thereof;
FIG. 3 is a top plan view thereof; and,
FIG. 4 is a side elevation view thereof, with all other side views looking the same.
